[57] **CLAIM**

The ornamental design for a shingle removal tool, as shown and described.

DESCRIPTION

FIG. 1 is a top and side perspective view of a shingle removal tool showing my new design;

FIG. 2 is a right side elevational view thereof, the left side elevational view being a mirror-image;

FIG. 3 is a top plan view thereof;

FIG. 4 is a bottom plan view thereof;

FIG. 5 is a front elevational view thereof; and,

FIG. 6 is a rear elevational view thereof.
